DISPLAY BOARD FOR SIDING SHINGLES

Kurt Schwarz, Fair Lawn, N.J., assignor to Supradur Corporation of New York, New York, N.Y., a corporation of New York

Filed May 13, 1968, Ser. No. 11,897

Term of patent 7 years

Int. Cl. D6—01

U.S. Cl. D80—5

FIG. 1 is a front elevational view of a display board for siding shingles, showing my new design;

FIG. 2 is a bottom plan view thereof;

FIG. 3 is a cross sectional view taken on line 3—3 of FIG. 1; and

FIG. 4 is an end elevational view thereof.

I claim:

The ornamental design for a display board for siding shingles, as shown.
